UNITED STATES PATENT OFFICE

TIDEMAN M. LILLEBERG, OF CHICAGO, ILLINOIS, ASSIGNOR TO NYE TOOL & MACHINE WORKS, OF CHICAGO, ILLINOIS, A CORPORATION OF ILLINOIS

VISE

Application filed February 4, 1929. Serial No. 337,339.

My invention relates more particularly to vises of the type comprising a base presenting a portion against which the article, as for example a pipe, to be clamped, is seated, a flexible element by which the article is clamped in the vise, and means for tightening the element against the article.

One of my objects is to provide a novel, simple, strong, and economical construction of vise; another object is to provide, as a part separable from the base, a jaw member against which the article is clamped which shall present a relatively long bearing surface for the article, a portion of which bearing surface directly opposes the flexible element thereby avoiding buckling of the article, especially in the case of a pipe; to provide such a jaw member which shall be inexpensive of construction, and may be readily assembled with, and removed from, the base of the vise; another object is to provide a construction of connection between the free end of the flexible element and the base which will not be liable to impairment under the forces to which it is subjected in the clamping operation; and other objects as will be manifest from the following description.

Referring to the accompanying drawings:

Figure 1 is a plan sectional view of a vise constructed in accordance with my invention.

Figure 2 is a view in side elevation thereof with certain of the parts broken away.

Figure 3 is a section taken at the line 3 on Fig. 1 and viewed in the direction of the arrow.

Figure 4 is a section taken at the line 4—4 on Fig. 1 and viewed in the direction of the arrows; and

Figure 5, a fragmentary sectional view taken at the line 5 on Fig. 1 and viewed in the direction of the arrow.

The preferred illustrated embodiment of my invention comprises a base 5 at which the device is adapted to be secured to a support, as for example to the top of a table, as by bolts passing through openings 6 in the base.

The base 5 is formed of a ribbed attaching plate section 7 in which the bolt-receiving openings 6 are located, and at one end of the section 7 with parallel vertical, relatively

heavy, wall plate sections 8 which are spaced apart and are connected together by an integral horizontal web 9 located between the upper and lower edges of the plate portions 8 and vertical web portions 10 located at the ends of the web portion 9 and set in from the ends of the plates 8 as shown, these various parts of the base being shown as formed integrally, as by casting them as a unit construction.

The upper edge portions of the plates 8 are recessed, as represented at 11 to receive a jaw member 12 which is of such length as to cause it to span the space between the plate portions 8 and preferably extend at its ends beyond these plate portions, as shown.

The jaw member 12 is shown as containing recesses 13 at opposite sides thereof having upwardly and inwardly inclining bottom portions 14 which are located in registration with the space between the plate portions 8, these recesses being arcuate in plan as shown in Fig. 1.

The upper surface of the jaw member 12 is serrated throughout the length of the jaw member as represented at 15, it being noted that the teeth 15 at the central portion of the jaw member and relative to which the longitudinal axis of the object to be clamped in the vise, would extend, are continuous throughout the length of the jaw member thereby providing a relatively long clamping surface for engagement by the article and which surface intersects the vertical plane in which the chain element of the vise, as hereinafter described, extends when in clamping position.

The jaw member 12 is held in place preferably by a screw represented at 16 which extends upwardly through an opening 17 in the web 9 and screws at its upper, threaded end into a threaded opening 18 in the jaw member 12.

The flexible element, shown as a chain, for clamping the article in the vise, as for example, the pipe shown at 19, is represented at 20, one end of this chain being shown as pivotally connected by a pin 21 with spaced apart ears 22, between which the chain extends and depending from the outer end of 100

a lever 23 located between the plates 8 and fulcrumed thereon as represented at 24, the lever 23 cooperating with a threaded actuating rod 25 engaging at its threads with the threaded opening 26 of a sleeve-like boss 27 shown as integrally formed with the plate portions 8. The rod 25 is positioned to bear against the outer, free, end of the lever 23 for exerting a tightening action on the chain 20, the outer end of the rod 25 being shown as 10 provided with a handle 28 for operating it.

The opposite end of the chain 20 is adjustably connected with the base 5 to adapt the device for the clamping of articles of widely different diameters. The chain shown comprises a series of links 29 adjacent ones of which are connected together by pins 30 extending outwardly beyond the links 29 as shown and in accordance with common practice. The end of the chain provided for adjustable connection with the base 5 as stated extends into the space between the plates 8 which latter are provided on their inner surfaces with portions 31 integral therewith and 20 each shaped to present an upper pair of recesses 32 and 32^a and a lower pair of recesses 33 and 33^a.

The recesses 32^a and 33^a are disposed in planes below the recesses 32 and 33, respectively, and the recesses 32 and 33 and 32^a and 33^a are spaced apart vertically a distance corresponding with the spacing of adjacent pins 30 and with which the ends of adjacent ones of these pins may be selectively interlocked in the adjustment of this end of the chain, as for example with the recesses 32 and 33 as shown by Fig. 3. The feature of providing upper and lower recesses spaced apart as stated is of advantage as the chain is there- 40 by anchored very securely to the base and danger of breakage of the parts is minimized; and the feature of providing the recesses 32^a and 33^a below the recesses 32 and 33, respectively, is of advantage as it provides 45 for closer adjustment of the chain.

The feature of providing the jaw member 12 and positioning the chain relative thereto as shown, is of advantage as a firm grip may be obtained on articles of widely different 50 diameters and with the minimum danger of crushing or otherwise distorting the articles.

While I have illustrated and described a particular construction embodying my invention, I do not wish to be understood as 55 intending to limit it thereto as the same may be variously modified and altered without departing from the spirit thereof.

What I claim as new, and desire to secure 60 by Letters Patent, is:

1. A vise comprising an attaching plate provided with an upstanding wall, an up- 65 standing wall parallel to and substantially coextensive with the first mentioned wall, 130 web means connecting said walls, said walls

above the web means having cutaway por- 70 tions, a jaw disposed over the web means and in said cutaway portions, a fastening means between the web means and jaw, a fulcrum member connecting said walls, a lever mov- 75 able between the walls and pivoted on said fulcrum member, a flexible clamping element connected to the lever, means whereby the flexible element may be secured in anchored relation to said walls, and an adjusting means 80 mounted by one of said walls and operable against said lever.

2. A vise comprising an attaching plate having an upstanding wall at one edge thereof, said wall being elongated and projecting 85 at one side beyond the plate, an upstanding wall parallel to and substantially coextensive with said first-mentioned wall, a hollow web means integral with said walls, said walls above said web means having cutaway por- 90 tions, a jaw disposed over the web means and engaging said cutaway portions, a fastening 95 extending through the web means and engaging the jaw to hold the same in place, a fulcrum member connecting said walls and disposed remote to the plate, a lever operable 100 between said walls and pivoted on said fulcrum member, a flexible clamping element secured to the lever, means whereby said clamping element may be anchored relatively 105 to said walls, said jaw at opposite sides thereof being cutaway to accommodate the flexible element when engaged with relatively small work, and adjusting means mounted on one 110 of said walls and operable against said lever.
